Patented June 5, 1962

192,955

BATHTUB SEAT

Curtis Moore, Forest City, Iowa

Filed May 31, 1960, Ser. No. 60,781

Term of patent 14 years

(Cl. D4—4)

FIG. 1 is a perspective view of a bathtub seat, on an enlarged scale, showing my new design,

FIG. 2 is a top plan view thereof,

FIG. 3 is a bottom plan view thereof,

FIG. 4 is a side elevational view thereof,

FIG. 5 is an enlarged elevational view of one end thereof, and

FIG. 6 is an enlarged elevational view of the opposite end thereof.

I claim:

The ornamental design for a bathtub seat, as shown.
